Attorney

UNITED STATES PATENT OFFICE.

WALTER A. FELTON, OF HASKELL, NEW JERSEY.

BOOT-DRYING DEVICE.

1,281,927.

Specification of Letters Patent. Patented Oct. 15, 1918.

Application filed March 29, 1918. Serial No. 225,496.

To all whom it may concern:

Be it known that I, WALTER A. FELTON, a citizen of the United States, residing at Haskell, in the county of Passaic and State 5 of New Jersey, have invented certain new and useful Improvements in Boot-Drying Devices, of which the following is a specification.

This invention relates to new and useful 10 improvements in boot drying devices and the primary object of the invention is to provide a means for drying wet boots, shoes or the like which is accomplished by circulation of a current of warm air through the 15 interior of the boot or shoe so as to dry the same in a short length of time. This device comprises a hollow standard on which the boot or shoe is adapted to be positioned, and said standard is adapted to be placed on a 20 stove and is so constructed that warm air passes therethrough and is circulated within the interior of the boot or shoe to dry the same.

Another object of the invention is to provide 25 a device of this character which is easily and simply constructed, inexpensive to manufacture, and one which will be very efficient in operation.

With these and numerous other objects in 30 view my invention consists of the novel features of construction, combination and arrangement of parts which will be herein referred to and more particularly pointed out in the specification and claims.

35 In the accompanying drawings:

The figure illustrates a vertical section through the device, showing a boot in dotted lines positioned thereon.

The numeral 1 designates a hollow standard 40 having an enlarged base portion 2 that is provided with a plurality of perforations 3 adjacent its lower edge. This base portion of the standard is adapted to be positioned on a stove and air that enters the standard through the perforations 3 will consequently be heated before passing upwardly through the interior portion of the standard.

The standard 1 is provided with tapering 45 walls and an enlarged head 4 that has its flat top provided with a plurality of perforations 5 therein and positioned on said top are spacing members 6 that are adapted to space the adjacent surface of the boot therefrom, as clearly shown in figure of the drawings.

The standard 1 is provided with an opening 7 through the wall thereof that has an outwardly projecting surrounding flange 8 that likewise extends upwardly and is internally threaded. Adapted to be positioned in said flange and cooperatively engaging the threads thereof is a short length upwardly and outwardly extending pipe 9 which is consequently detachably connected 85 with the standard. The short length pipe 9 is provided with a flat closed outer end 10 that has therein a plurality of perforations 11, and secured to said flat top which is disposed in a single plane with the flat top of 90 the enlarged head of the standard are a plurality of spacing members 12 that space the adjacent portion of the boot therefrom so as to permit the air to escape through the perforations. Positioned within the standard 75 1 and extending across the same at an angle in alignment with the top face of the pipe 9 is a deflector plate 13, that is provided with a plurality of apertures 14 whereby the air is permitted to pass therethrough 80 into the head portion of the standard, and a certain portion thereof will be deflected and will pass out through the short length pipe 9.

In operation, this standard is adapted to 85 be positioned on a stove or the like and a boot arranged thereon as is clearly shown in dotted lines in the figure of the drawings. When positioned on a heated surface the air that enters the base of the standard through 90 the perforations 3 will be heated and consequently will rise rapidly through the standard, and pass out through the perforated enlarged head thereof and circulate within the interior of the boot to rapidly 95 dry the same. A certain amount of the heated air will be deflected by the plate 13 out through the short length pipe 9 and will be carried to the toe portion of the boot where it passes out through the end of the 100 pipe and circulates within the same to dry that portion of the boot. This branch pipe is a supplemental heated air carrying means, which will cause the heated air to circulate throughout the entire interior of the boot so 105 as to dry the same in a minimum length of time.

The top of the enlarged head and flat closed end of the branch pipe 9 are disposed in a single plane so that the boot may rest 110 easily thereon. The spacing members on these flat surfaces will hold the adjacent por-

tions of the boot therefrom so as to permit the heated air to freely escape through the perforations in said parts. Although this device is primarily intended for drying boots it is obvious that the same may be formed smaller and is adapted for drying shoes, etc.

From the foregoing description taken in connection with the accompanying drawings, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Having fully described my invention, what I claim is new, and desire to secure 20 by Letters Patent, is;

1. A device of the class described including a hollow standard having a perforated base, a laterally and upwardly extending branch pipe connected therewith, and the 25 other end of the pipe and head of the stand-

ard being disposed in a single plane and perforated.

2. A device of the class described including a hollow standard having a perforated base, a laterally and upwardly extending 30 branch pipe connected therewith, the other end of the pipe and the head of the standard being disposed in a single plane and perforated, and a perforated deflector plate arranged across standard above the 35 branch pipe whereby a certain amount of air will be deflected through the same.

3. A device of the class described including a hollow standard having a perforated base, a laterally and outwardly extending 40 branch pipe detachably connected therewith, a perforated deflector plate arranged across said standard above the branch pipe, the head of the standard and end of the branch pipe being disposed in a single plane and 45 perforated, and spacing members positioned on said last mentioned parts.

In testimony whereof I affix my signature hereto.

WALTER A. FELTON.
